UNITED STATES PATENT OFFICE.

ARTHUR ERNEST JERRAM, OF LEICESTER, ENGLAND, ASSIGNOR TO UNITED SHOE MACHINERY COMPANY, OF PATERSON, NEW JERSEY, A CORPORATION OF NEW JERSEY.

SEWING-MACHINE.

1,162,696.

Specification of Letters Patent. Patented Nov. 30, 1915.

Original application filed August 4, 1909, Serial No. 511,216. Divided and this application filed July 18, 1912. Serial No. 710,191.

To all whom it may concern:

Be it known that I, ARTHUR E. JERRAM, a subject of the King of Great Britain, residing at Leicester, in the county of Leicestershire, England, have invented certain Improvements in Sewing-Machines, of which the following description, in connection with the accompanying drawings, is a specification, like reference characters on the drawings indicating like parts in the several figures.

This invention relates to sewing machines, and more particularly to sewing machines of the type in which the work is fed by the lateral movements of the needle.

The object of the invention is to improve the construction, arrangement and mode of operation of sewing machines of this class.

With the above object in view, certain features of the invention relate to improved and simplified needle actuating devices by which the needle is projected through and withdrawn from the work, and is moved laterally in timed relation to its work piercing or retracting movements in a certain and reliable manner.

A further feature of the invention consists in the provision of a needle straightening device for placing the needle in correct work feeding position before the work is fed.

A still further feature of the invention contemplates the provision of an assistant feeding device arranged to engage the forward side of the needle, and to move in unison with the needle during its lateral movements to assist in feeding the work.

Further features of the invention consist of certain constructions and combinations hereinafter described and claimed, the advantages of which will be obvious to one skilled in the art from the following description.

In the accompanying drawings illustrating the invention in the best form at present known to the inventor, Figure 1 is a view in side elevation of a sewing machine embodying the invention, with parts of the casting broken away and parts of the machine shown in section; Fig. 2 is a view in front elevation of the machine; Fig. 3 is a sectional view taken substantially on the line 3-3 of Fig. 1; Figs. 4, 5 and 6 are detail views illustrating particularly a portion of the needle actuating mechanism in different positions; Fig. 7 is a detail sectional view

showing a portion of the needle actuating mechanism; Fig. 8 is a detail view partly in section illustrating particularly the needle actuating mechanism; and Fig. 9 is a detail view illustrating the thread deflector detached.

The present application is a division of an application Serial No. 511,216, filed August 4, 1909, upon which Patent No. 1,120,201, dated December 8th, 1914, was granted. Certain parts of the machine illustrated in the drawings are only briefly described in this application, inasmuch as they form no part of the present invention, and are fully described in the application referred to above.

The sewing machine illustrated in the drawings forming a part of this application comprises a straight eye pointed needle indicated at 1, a presser foot 2 for holding the work on the work table 3, a take-up 4, a stitch length measurer 5, a thread lock 6, an oscillating shuttle 7 provided with a hook, for engagement with the loop of needle thread pushed through the work by the needle, and a deflector 8 for bringing the needle thread into the path of the shuttle hook.

The work is fed by the lateral or transverse movement of the needle while the needle is in the work. The movements imparted to the needle by the needle actuating mechanism to cause the needle to pierce the work and move laterally to feed the work, are substantially as follows: Starting with the needle in position above the work and the length of a stitch in advance of the last needle hole, the needle is projected downwardly through the work, and after it reaches its limiting position it is raised a sufficient distance to throw out a loop of thread between the needle eye and the work. After the needle is raised a pause occurs in the vertical movement of the needle during which the needle is moved laterally or transversely to feed the work. When the work has been fed a distance equal to the required length of stitch the needle is lifted from the work and is then moved laterally to bring it to its initial position ready to again perform the same cycle of operations. In order to enable the needle to be actuated as described, the needle is mounted on a needle bar arranged to reciprocate vertically in a

transversely movable frame 9. The vertical movements are imparted to the needle by mechanism connected with the needle bar and acting to reciprocate the needle bar vertically in the frame 9, and the lateral movements are imparted to the needle by mechanism which acts in timed relation to the mechanism for reciprocating the needle bar vertically to impart transverse or lateral movements to the frame 9. The mechanism for reciprocating the needle bar in the illustrated embodiment of the invention comprises a continuously rotating member 10 mounted on the main shaft 11 of the machine, upon which member is mounted a lever 12 pivoted at 13 eccentrically on said rotary member and connected with the needle bar 14 by means of a link 15. The lever 12 is provided with an arm 12^a which projects through a slot 16 in the rear side of the member 10, and carries a cam roll engaging a cam groove 18^a in a stationary member 18 mounted on the machine frame. The cam groove 18^a is constructed in such a manner that the lever 12 is moved angularly about its pivot with relation to the rotary member 10 during the rotation of said member, thereby causing the point of connection of said lever with the link 15 to move in an irregular path, and imparting a variable movement to the needle bar and the needle. It will be noted from an inspection of Figs. 4, 5, 6 and 7 that the point of connection of the lever 12 with the link 15 is caused to pause for some considerable time adjacent the axis of the main shaft 11 during the rotation of the member 10. This pause occurs after the needle has penetrated the work and has been raised a sufficient distance to cause the loop of needle thread to be thrown downwardly therefrom, and continues while the shuttle engages and passes through the loop of needle thread, and also gives time for the needle to move forward and feed the work.

The needle bar 14 is arranged to reciprocate vertically in the transversely movable frame 9, and in order to support said frame so as to permit it to move transversely, the frame is mounted upon a hollow rod 19 arranged to slide in bearings in the machine frame. The frame is steadied in its transverse movements by a guide comprising a plate 20 provided with a groove to receive a rib 21 on the frame 9. The slide rod 19 is provided at its left-hand extremity (Fig. 2) with a die 22 pivoted upon a pin which extends through a slot in the slide rod 19 and is secured to the end of a pendant arm 23 carried by a rock shaft 24 extending from the front to the rear of the machine. The other end of the rock shaft 24 carries a curved arm 25 connected at its extremity with a toggle mechanism. Said toggle mechanism comprises two members 26 and

27 jointed together by means of a pin 28, the member 26 being pivoted at 28 to the extremity of the arm 25. The member 27 is arranged for adjustment about an axis which is substantially in alinement with the central joint of the toggle in the position which said toggle assumes at the beginning of the work feeding movement, and to this end said member is connected at 30 to a member 31 pivoted at 32 on the machine frame. The axis of the member 31 is arranged so that it is substantially in alinement with the axis of the central joint of the toggle when the toggle is in position at the beginning of the work feeding movement. In order to secure the member 31, and thereby the member 27 of the toggle, in adjusted position, a screw threaded rod projects rearwardly from the member 31 through a slot 33 in the casing of the machine, and a clamping nut 34 threaded on said rod engages the frame at the sides of the slot. In order to reciprocate the central joint of the toggle, and thereby impart transverse movements to the frame 9, a cam roll 35 is mounted upon the pin 28 which connects the two toggle members, and is arranged to engage a cam groove 36 in the face of the cam disk 37. It is to be noted that by arranging the member 27 of the toggle for adjustment about an axis which is in alinement with the central joint of the toggle when the toggle is in position at the beginning of the work feeding movement, the length of the transverse movement of the frame 9 and of the needle may be varied to vary the length of feed while the needle is caused to assume the same position at the beginning of its work feeding movement, regardless of the position in which the toggle member 27 is adjusted.

The shuttle 7 is arranged to oscillate in a plane parallel with the line of feed and with the line of the seam, and to this end is arranged in a guideway 38 in the forward portion of the machine frame below the work table 3. The shuttle is driven by an oscillatory shuttle driver 39 also arranged to oscillate in a plane parallel with the plane of the needle and the line of the seam. The shuttle driver is oscillated through somewhat over three-quarters of a revolution to impart a corresponding oscillatory movement to the shuttle. The shuttle driver consists of a projection which fits into a suitably formed recess in the frame of the shuttle, said projection being formed on a member 40 carried upon an oscillatory shaft 41 to which oscillatory movements of somewhat over three-quarters of a revolution are imparted by suitable connections from a cam actuated lever 41^a.

The shuttle driver is provided with a needle straightening device indicated at 42, which consists of an extension from the

driver. This extension projects through the circular raceway of the shuttle and during the last part of the retrograde movement of the shuttle driver, engages the needle from the forward or left-hand side (Fig. 2), and if the needle has been deflected toward the loop-taking hook of the thread deflector 8 in penetrating the work, the needle straightening device operates to push the needle up against the forward end of the slot in the work supporting table 3 into correct position for feeding the work and for coöperation with the loop-taking hook of the thread deflector.

15 In order to feed the work with precision and uniformity, notwithstanding the flexibility of the needle, an assistant feeding device is provided to engage the forward side of the needle below the work table 3 and to move in unison with the needle during its lateral movements. The assistant feeding device comprises a plate 43 carried by a rocking sleeve or rocker 44 arranged to oscillate about the shaft 41 which carries the shuttle driver. Said sleeve carries at its rear end an arm 45 connected by a link 46 with the arm 25 of the rock shaft 24. By means of these connections the frame 9, the needle and the assistant feed plate 43 are moved laterally or transversely in unison. The connection of the assistant feed plate with the mechanism for actuating the needle transversely in the direction of feed enables the extent of the lateral movement of the needle and assistant feed plate to be simultaneously adjusted. As the needle moves laterally to feed the work the left-hand side or edge (Fig. 2) of the plate 43 engages the forward side of the needle below the work table and advances in the direction of feed with the needle.

It is to be noted that the needle straightening device 42 and the assistant feed plate 43 operate to place the needle in correct work feeding position at the beginning of the feeding movement of the needle, and that therefore these devices positively determine the feeding movement of the needle.

While the invention has been illustrated as embodied in a machine in which the work is fed by the lateral movement of the needle, it is to be understood that certain features of the invention may be embodied to advantage in machines in which the work is fed by a device or devices other than the needle. It is also to be understood that except as defined in the claims the invention is not limited to any particular machine or type of machine, or to any particular construction or arrangement of parts.

60 Having explained the nature and object of the invention, and having described a machine embodying the same in its preferred form, what is claimed is:—

1. A sewing machine, having, in combination, stitch forming devices including a work

feeding needle, means to actuate the needle, and a needle straightening device for the needle movable with relation to the needle in a direction transverse thereto.

2. A sewing machine, having, in combination, stitch forming devices including a work feeding needle, means to actuate the needle, and a needle straightening device movable with relation to the needle in a direction transverse thereto and arranged to engage the needle and place it in correct work feeding position before the work is fed.

3. A sewing machine, having, in combination, a work feeding needle, means to actuate the needle, a shuttle, an oscillating shuttle driver, and a needle straightening device carried by the shuttle driver arranged to engage the needle at the end of the retrograde movement of the driver and place the needle in correct work feeding position before the work is fed.

4. A sewing machine, having, in combination, a work feeding needle, means to actuate the needle, a shuttle, a shuttle driver arranged to oscillate in a plane parallel with the needle and the line of feed, a needle straightening device carried by the shuttle driver and arranged to engage the forward side of the needle at the end of the retrograde movement of the driver and place the needle in correct work feeding position before the work is fed.

5. A sewing machine, having, in combination, a work feeding needle, means to actuate the needle, a rotating shuttle provided with a beak to engage the needle thread and pass the same about the shuttle, and a needle straightening device movable with relation to the needle in a direction transverse thereto and arranged to engage the needle and place the same in correct position to feed the work before the work is fed.

6. A sewing machine, having, in combination, a needle arranged to feed the work, and independently operating devices acting on opposite sides of the needle below the work for positively determining its work feeding movement.

7. A sewing machine, having, in combination, a work feeding needle, a shuttle arranged to oscillate in a plane parallel with the plane of the needle and the line of feed, and an oscillating assistant feeding device arranged to turn coaxially with the shuttle.

8. A sewing machine, having, in combination, a work feeding needle, means to actuate the needle, and independent needle positioning devices arranged to engage opposite sides of the needle below the work and place the needle in correct work feeding position before the work is fed.

9. A sewing machine, having, in combination, a needle, a needle bar, means for reciprocating the needle bar to move the needle into and out of engagement with the work,

comprising a rotary shaft, a disk carried on the front end of the shaft, a bell crank lever pivoted on the disk, a pivot stud for the lever extending through the lever and supported at each end in the disk, a link connecting one arm of the bell crank lever with the needle bar, a cam roll carried by the other arm of the bell crank lever, and a stationary member having an irregular cam 10 groove in which said cam roll engages.

10. A sewing machine, having, in combination, a needle, a needle bar, means for reciprocating the needle bar to move the needle into and out of engagement with the work, 15 comprising a rotary member, a bell crank lever pivoted eccentrically on said rotary member, a link pivotally connected with one arm of said lever at a point the distance of which from the pivot of the lever is greater 20 than the distance between the pivot of the lever and the axis of the rotary member, a pivotal connection between the other end of the link and the needle bar, a cam roll mounted on the other arm of said lever, and 25 a stationary member having an irregular cam groove in which said roll engages.

11. A sewing machine, having, in combination, a device for engaging and feeding the work, means for moving said device into 30 and out of engagement with the work, mechanism acting in timed relation to said means for reciprocating said device in the direction of feed comprising a toggle, connecting mechanism between said device and one of 35 the members of said toggle, a cam roll carried by the central joint of the toggle, a cam for engagement with the cam roll to actuate said toggle to reciprocate said device, and provision for adjustment of said toggle to 40 vary the extent of the reciprocatory movement of said device.

12. A sewing machine, having, in combination, a needle, a needle bar, a transversely movable frame in which the needle 45 bar is mounted arranged to reciprocate to carry the needle into and out of engagement with the work, means to reciprocate the needle bar, and means for reciprocating said frame comprising a rock shaft connected 50 with said frame, an arm on said rock shaft, a toggle comprising a toggle member connected with said arm, a second toggle member, a cam roll carried by said toggle, a cam

engaging said roll, an assistant feeding device comprising an assistant feed plate arranged on the opposite side of the work from the needle, a rock shaft on which said plate is mounted, an arm on said rock shaft, and a link connecting said arm with the arm on the first rock shaft. 60

13. A sewing machine, having, in combination, a needle, a needle bar, a transversely movable frame in which the needle bar is arranged to reciprocate to carry the needle into and out of engagement with the work, means to reciprocate the needle bar, and means for reciprocating said frame comprising a rock shaft connected with said frame, an arm on said rock shaft, a cam roll connected with said arm, a cam engaging 70 said cam roll, an assistant feeding device comprising a feed plate arranged on the opposite side of the work from the needle, a rock shaft on which said plate is mounted, an arm on said rock shaft, and a link connecting said last arm with the arm on the first rock shaft. 75

14. A sewing machine, having, in combination, a needle, a discoidal shuttle, an oscillating shuttle driver, and a needle straightening device consisting of a projection on the shuttle driver arranged to engage the needle during the backward movement of the shuttle driver.

15. A sewing machine, having, in combination, a needle, means for actuating the needle to feed the work, an auxiliary feeding device arranged to engage the needle below the work and move with the needle during the feed, a needle straightening device, and means for actuating said device to engage the needle and force it against the auxiliary feeding device. 85 90

16. A sewing machine, having, in combination, stitch forming devices including a work feeding needle, a discoidal shuttle, an oscillating shuttle driver, and an oscillating assistant feeding device arranged to oscillate coaxially with the shuttle driver. 95

In testimony whereof, I have signed my name to this specification in the presence of two subscribing witnesses.

ARTHUR ERNEST JERRAM.
